—ATTORNEY.

UNITED STATES PATENT OFFICE.

BLAS C. SILVA, OF PONCE, PORTO RICO.

CODE.

Application filed July 29, 1921, Serial No. 488,361. Renewed January 6, 1923.

To all whom it may concern:

Be it known that I, BLAS C. SILVA, a citizen of the United States, residing at Ponce, Porto Rico, have invented certain new and useful Improvements in a Code, of which the following is a specification.

In the different codes now commonly in use throughout the world it has been demonstrated that their capacity is very limited, thus the capacity in phrases of the Lieber's code (standard and the 5 letters) is 75,878, of the A. B. C. code (electric and telegraphic code is 25,400, of the A. B. C. code (5th edition improved) is 103,084, of the International telegraphic code is 99,999, of Bentley's (E. L.) complete telegraphic code is 31,462, of Western Union telegraphic code is 157,352, and, of Western Union telegraphic code (mammoth volume) is 362,400. It is the object of the present invention to provide a code of indefinite capacity in phrases and which may be used in a practical manner to great advantage and far more economically than those now commonly in use.

In the drawings:—

Figure 1 is a diagrammatical view showing the possibilities of the code, and

Figure 2 represents a page from a code book embodying the present invention.

The twenty five letters of the alphabet are used as a basis of my code. The twenty five letters of the alphabet correspond in my code to the numbers 0 to 24 of the first column as represented in the drawing. Thus the twenty five letters form the first group of signs, twenty five (25) in number, with only one letter each.

By combining each letter of the first or single letter group with all the letters of the same group, I obtain the second group of two letters each. With the first and second group I obtain $25^2 \times 25$ or 650 symbols.

By combining each symbol of the second group with the twenty five letters of the alphabet I obtain a third group of their letters each and bring the total to $25^3 \times 650$ or 16,275. Continuing this process by adding one of the letters of the alphabet to the third group of these letters each I obtain a fourth group of four letters each and bring the capacity to $25^4 \times 16,275$ or 406,900 symbols which is greater than the capacity of the Western Union telegraphic code (mammoth volume).

If this process were continued to the tenth group of ten letters each its capacity would be $25^{10} \times 25^9 \times 25^8 \times 25$ or 99,341,074,625,650, which, of course would never be necessary.

Referring to Figure 2 it will be noted that the columns starting with the third contain the phrases in various languages so as to be opposite to the corresponding code symbol in column 2.

Having thus described my invention what I claim as new is:

In a printed code, a series of columns, one of said columns containing numerals successively arranged, another of said columns containing the twenty five letters of the alphabet arranged in their usual sequence so as to form one group, a second group formed by combining each letter of the first group with all the letters of the same group, the third group being formed by combining the second group with the first group and the remaining columns containing phrases in various languages corresponding or represented by the letters in column two.

In testimony whereof I affix my signature in presence of two witnesses.

BLAS C. SILVA.

Witnesses:

JOSÉ M. DIAZ,
ANGEL ELERAMA.
